FLUID PRESSURE BRAKE

Clyde C. Farmer, Pittsburgh, and Ellis E. Hewitt,
Edgewood, Pa., assignors to The Westinghouse
Air Brake Company, Wilmerding, Pa., a corpo-
ration of Pennsylvania

Application October 27, 1931, Serial No. 571,314

30 Claims. (Cl. 303—35)

This invention relates to fluid pressure brakes, and more particularly to the type adapted to operate in accordance with variations in brake pipe pressure to control the brakes on a train.

5 In effecting an application of brakes, particularly on a long train, the brakes at the front end of the train apply in advance of applying the brakes at the rear end of the train, due to which the slack in the train tends to run in toward the front end of the train so harshly as to cause severe shocks, where the train is very long.

One object of our invention is to provide a fluid pressure brake system having improved means for delaying the build-up of brake cylinder pressure on cars at the head end of the train so as to obviate the above described condition.

In operating short trains, or in operating a train in high speed service, the degree of shock produced by the running in of slack, due to a 20 serial application of the brakes, is not so objectionable as when operating long trains, particularly at low speeds.

Another object of our invention is to provide a fluid pressure brake equipment having means 25 for delaying the build up of brake cylinder pressure at the front end of the train and improved means for rendering the delay means ineffective when operating short trains or when operating a train in high speed service.

30 Other objects and advantages will appear in the following more detailed description of the invention.

In the accompanying drawings; Fig. 1 is a diagrammatic view, mainly in section, of a fluid 35 pressure brake equipment embodying our invention and showing the various parts in the position assumed at the rear end of the train when the brakes are released; Fig. 2 is a view of a portion of the equipment shown in Fig. 1 and showing the 40 parts in the position initially assumed in the front portion of the train in effecting a release of the brakes; Fig. 3 is a view, similar to that shown in Fig. 2, but with the selector valve and other parts shown in the position assumed at the front end of the train after the brakes are released; Fig. 4 is a view similar to Fig. 2, with the apparatus shown in the act of moving the selector valve from the delay position shown in Fig. 3; and Fig. 5 is a view similar to Fig. 2 and showing 45 means operated to a position for rendering the selector valve inoperative.

As shown in the drawings, the fluid pressure brake equipment comprises a bracket 1 upon 50 which is mounted a triple valve device 2, an

emergency valve device 3; and a selector valve device and a selector cut-out device 5.

The triple valve device comprises a piston 6 having at one side a chamber 7 connected to the brake pipe 8, and having at the other side a valve 5 chamber 9 connected to an auxiliary reservoir 10. The piston 6 is provided with a stem 11 extending into valve chamber 9 for operating a main slide valve 12 and an auxiliary slide valve 13.

The emergency valve device 3 comprises a piston 14 having at one side a chamber 15 connected to the brake pipe 8 and at the other side a valve chamber 16 connected to a quick action chamber 17 through a passage 18. The piston 14 is provided with a stem 19 extending into valve 15 chamber 16 for operating a main slide valve 20 and an auxiliary slide valve 21. The main slide valve 20 is provided with a wing 22, and a roller 23 is pressed against wing 22 by means of a spring 24 for holding the main slide valve in engagement with its seat.

The selector valve device comprises a slide valve 25 disposed in a chamber 26 which is connected to the auxiliary reservoir 10, and a movable abutment 27 for moving said slide valve from the 25 unrestricted build-up position shown in Fig. 1 to the hold back or delay position shown in Figs. 2 and 3, a projection 28 being provided in the right hand end of the slide valve for engagement by said abutment. 30

The movable abutment 27 is open at one side to valve chamber 26 and has at the opposite side a chamber 29 connected to the brake pipe 8. A spring 30 in valve chamber 26 engages the abutment for opposing movement of said abutment 35 toward the left hand, and normally urges said abutment into engagement with stop lugs 31 which extend from the casing into chamber 29.

The abutment 27 is provided for moving the slide valve 25 from the position shown in Fig. 1, 40 leftwardly to the position shown in Fig. 2, as above described. For moving said slide valve in the reverse direction, a lever 32 is provided. The lever 32 is pivotally mounted on a suitable pin 33 carried by the casing. One arm of said lever extends through an opening 34 in the slide valve and into a chamber 35 formed within said slide valve, and a spring 36 is interposed between the end of said lever arm and the slide valve.

A movable abutment 37 is provided for operating the lever 32, and is connected to a downwardly extending arm of said lever by means of a push rod 38, which is provided with a slot 39 through which an operating pin 40, carried by the lever arm, extends. The abutment 37 has 55

at one side a chamber 41 and has at the opposite side a chamber 42 which is at all times open to the atmosphere, such as by means of an atmospheric passage 43. A spring 44 is provided in chamber 42 for urging the abutment 37 into engagement with stop lugs 45 formed in chamber 41.

The lever 32 is provided with a lug 46 and clearance is provided in the casing, as shown in Fig. 1 for normally permitting said lug to freely move toward the left hand with lever 32, when said lever is operated by movement of the slide valve 25 to the delay position, as shown in Figs. 2 and 3. For preventing such movement of lever 32, and thereby preventing such delayed application of the brakes, as will be hereinafter described, a plunger 47 is provided and is adapted to be moved into the space between lug 46 and the casing, by means of a movable abutment 48.

20 The abutment 48 has at one side a chamber 49, and at the other side a chamber 50 which is connected to the atmosphere through passage 51, chamber 42 and passage 43. A spring 52 in chamber 50 normally urges the abutment 48 into engagement with a seat rib 53 in the casing.

Projecting from the abutment 48 is a hollow sleeve-like stem 54 having an opening through its outer end through which the plunger 47 freely extends. The plunger 47 is provided with a sleeve-like extension slidably disposed in the stem 54 and having a shoulder 55 adapted to normally engage a corresponding shoulder in the stem 54 due to the pressure of a spring 56 interposed between the abutment 48 and the extension of the plunger 47. By these means, relative movement of the abutment 48 to the plunger 47 is provided so that the abutment 48 may be moved into engagement with a stop 118 in chamber 50 without exerting a heavy pressure on the plunger 47, the pressure on the plunger under this condition being only that of spring 56 which is only of light value. The reason for this particular telescopic construction will be explained more in detail hereinafter.

45 Preferably incorporated in the bracket 1 is the usual brake pipe vent valve mechanism comprising a vent valve 58 contained in a chamber 59 connected to brake pipe 8, and a piston 60 for unseating said vent valve against the opposing pressure of a spring 61. The piston 60 has at one side a chamber 62 and at the opposite side a chamber 63 which is open to the atmosphere through a chamber 64 and an atmospheric passage 65.

55 In operation, to initially charge the brake equipment, fluid under pressure is supplied to the brake pipe 8 in the usual manner and flows from the brake pipe through pipe and passage 66 to the vent valve chamber 59, the emergency valve piston chamber 15 and to a chamber 67. From chamber 67 fluid under pressure flows through passage 68 to chamber 29 at one side of the selector valve abutment 27 and also from chamber 67 through a plurality of ports 69 and a chamber 70 to the triple valve piston chamber 7.

With the triple valve parts in the release position shown in Fig. 1 of the drawings, fluid under pressure flows from chamber 7 through feed passage 71 to valve chamber 9 and from said chamber through passage 72 to the auxiliary reservoir 10 and to the selector valve chamber 26.

70 Fluid under pressure also flows from the triple valve slide valve chamber 9 through a port 73 and connected passage 74 in the mainslide valve 12 to passage 75 which is connected to an inshot

reservoir 76 and also from passage 74 through passage 77 to an emergency reservoir 78. The emergency reservoir 78 is connected through passage 77 and passage 79 to chamber 49 at one side of the delay cut-out abutment 48 and also through passage 77 and a passage 80 to the seat of the emergency slide valve 20. In this manner, the auxiliary reservoir 10, emergency reservoir 78 and inshot reservoir 76 are charged up to brake pipe pressure and it will be noted that the selector valve chamber 26 is at all times supplied with fluid at the pressure in the auxiliary reservoir, and chamber 49 at one side of the cut-out abutment 48 is always charged with fluid at emergency reservoir pressure. The cut-out abutment is at all times maintained in the position shown in Fig. 1 by means of spring 52 except when the brake pipe pressure is increased for short train operation or high speed service, as will be hereinafter described.

20 With the emergency valve parts in the position shown in the drawings, fluid under pressure flows from the piston chamber 15 through passage 82, past a check valve 83 and through passage 84 to valve chamber 16 and from thence through passage 18 to the quick action chamber 17, thereby charging said chamber to brake pipe pressure.

30 In charging a train initially and in releasing the brakes after an application, it is customary for the usual brake valve device (not shown) to be turned first to release position in which fluid at the high pressure carried in the usual main reservoir is supplied directly to the brake pipe, so as to charge the brake pipe at a rapid rate. Then, after a certain lapse of time, the 35 brake valve device is turned from release position to running position in which fluid at the reduced pressure supplied by the usual feed valve device is supplied to the brake pipe. In charging the brake pipe in this manner, the 40 brake pipe pressure in the head portion of the train is built up at a rapid rate for hastening the charging of the brake pipe at the rear end of the train.

45 In the front portion of the train, the rate of increase in brake pipe pressure exceeds the rate at which the auxiliary reservoir 10 is charged to a degree sufficient for the brake pipe pressure acting in chamber 29 at one side of the selector valve abutment 27 to move said abutment toward 50 the left hand into engagement with a stop rib 85 against the opposing pressures of spring 30 and the slower increasing auxiliary reservoir pressure acting in chamber 26. This movement of abutment 27, as illustrated in Fig. 2, shifts 55 the slide valve 25 to the hold back or delay position shown in Figs. 2 and 3, in which position the supply of fluid under pressure from the triple valve device 2 to the brake cylinder 86 is retarded in effecting an application of the 60 brakes, as will be hereinafter described. When the auxiliary reservoir pressure acting in the selector valve chamber 26 becomes built up to that carried in the brake pipe, as supplied by the usual feed valve device, the pressure of spring 30 moves the abutment 27 to its right hand 65 position shown in Fig. 1, this movement of the abutment being relative to the slide valve 25 which remains in the position shown in Fig. 2.

70 When the abutment 27 moves the slide valve 25 as above described, the lever 32 tends to be rotated by the pressure of spring 36 and to permit such rotation relative to the abutment 37, the push rod 38 projecting from said abutment is provided with the slot 39.

In the rear portion of the train, the rate of increase in brake pipe pressure being slow relative to the rate of increase in brake pipe pressure in the front portion of the train, the auxiliary reservoir 10 is adapted to be charged through the feed passage 71, in the manner hereinbefore described, at substantially the same rate as the brake pipe pressure increases. As a result, an insufficient differential of pressures is 5 established on the opposite sides of the selector valve abutment 27 to move said abutment against the opposing pressure of spring 39. Consequently, in the rear portion of the train, the selector valve abutment 27 and slide valve 10 15 25 remain in the position shown in Fig. 1, in which fluid under pressure supplied by the triple valve device in effecting an application of the brakes, is adapted to flow to the brake cylinder 86 at a faster rate than at the head end of the 20 train, as will be hereinafter described.

In the release position of the triple valve device 2, as shown in Fig. 1, the brake cylinder 86 is connected to the atmosphere through pipe 25 and passage 87, cavity 89 in the selector slide valve 25, passage 90, cavity 91 in the triple valve slide valve 12, release choke plug 92 and an atmospheric passage 94. In the front portion of the train, when the selector slide valve 25 is in the left hand position shown in Fig. 3, passages 30 87 and 90 are disconnected by said slide valve, and the brake cylinder is open to the atmosphere through passage 87, choke plug 88 and passage 90.

When the triple valve device is in release position, chamber 41 at one side of the abutment 37 is open to the atmosphere through passage 95, cavity 96 in the triple valve slide valve 12 and atmospheric passage 97.

If it is desired to effect a service application 40 of the brakes, fluid under pressure is gradually vented from the brake pipe 8 and consequently from the triple valve piston chamber 7 and emergency valve piston chamber 15.

When the brake pipe pressure in piston chamber 45 7 is thus reduced a certain degree below auxiliary reservoir pressure acting on the opposite side of the triple valve piston 6, said piston is operated to move the slide valves 12 and 13 to service position, in which the piston engages a gasket 98. In this position, fluid under pressure is permitted to flow from the inshot reservoir 76 through passage 75, a cavity 99 in the triple valve slide valve 12, through a passage 100, past a check valve 101 and through a passage 102 to 50 the seat of the selector slide valve 25, and at the same time, fluid under pressure is permitted to flow from the triple valve chamber 9 and the connected auxiliary reservoir 10 through the service port 103 in the main slide valve 12, which 55 port is uncovered by the auxiliary slide valve 13 in service position, and from port 103 to passage 98 leading to the seat of the selector slide valve 25.

In the front portion of the train, where the 60 selector slide valve 25 is in the position shown in Fig. 3, fluid under pressure supplied to passage 102 flows rapidly through a cavity 104 to passage 87 and from thence to the brake cylinder 86.

The fluid under pressure from the inshot reservoir 76 is thus permitted to flow to and equalize in the brake cylinder 86 at a rapid rate. The 65 degree of brake cylinder pressure thus obtained, however, is merely sufficient to effect a predetermined movement of the usual brake cylinder

piston (not shown) and is not adapted to provide effective braking force.

Since passage 90 is lapped by the selector slide valve 25, fluid under pressure supplied thereto by the operation of the triple valve device, flows 5 through the choke plug 88 at a slow rate to passage 87 leading to the brake cylinder. As a result, after the initial inshot of fluid under pressure to the brake cylinder from the inshot reservoir 76, the rate of supply to the brake cylinder 10 10 is governed by the flow area of the choke plug 88, and the check valve 101 is provided to prevent flow to the inshot reservoir 76 when the brake cylinder pressure is increased above the reduced pressure in said reservoir. 15

Fluid at the pressure supplied to the brake cylinder 86 flows from the brake cylinder passage 87 through a passage 105 to the seat of the triple valve slide valve 12 and from thence through passage 106 in said slide valve to passage 95 leading to chamber 41 at one side of the abutment 37. When a predetermined brake cylinder pressure is obtained by the supply through choke plug 88, as hereinbefore described, said pressure acting in chamber 41 overcomes the opposing 25 pressure of spring 44 on the abutment 37 and moves said abutment toward the left hand and into engagement with a stop rib 107. This movement of the abutment 37 operates the push rod 30 38 which turns the lever 32 in a clockwise direction. This rotation of lever 32 tends to compress the spring 36, the pressure of which is sufficiently increased to move the slide valve 25 as shown in Fig. 4, from the hold back position shown in Fig. 3 of the drawings to the unrestricted brake cylinder build-up position shown in Fig. 1. This movement of the slide valve 25 ceases in the latter position due to engagement of the projection 28 with the abutment 27. When the slide valve 25 is moved to the position shown 40 in Fig. 1, passages 87 and 90 are connected through cavity 89 in said slide valve and forms an unrestricted by-pass around the choke plug 88 thereby permitting a faster rate of flow of 45 fluid under pressure to the brake cylinder.

It will now be evident that fluid under pressure is supplied to the brake cylinder at the head end of the train in three distinct stages, namely, the initial inshot, then a slow rate of build-up for a predetermined length of time and finally an unrestricted build-up. The purpose of the initial inshot has been hereinbefore described. The slow rate of build-up is adapted to so retard the application of brakes at the head end of the train as to permit a gradual and gentle gathering of 55 the slack, after which, the unrestricted build-up occurs to provide the desired brake cylinder pressure for retarding the train.

At the rear of the train, the selector slide valve 25 is in the position shown in Fig. 1 of the drawings for reasons hereinbefore described. In this position, passage 102, to which fluid under pressure is supplied from the inshot reservoir 76, is lapped, and passages 87 and 90 are connected by cavity 89 in said slide valve. Thus, in effecting 60 an application of brakes at the rear end of the train, there is no inshot of fluid under pressure to the brake cylinder as in the front end of the train, but fluid under pressure supplied by the triple valve device flows to the brake cylinder at 70 an unrestricted rate. By thus applying the brakes in the rear portion of the train at a more rapid rate than the brakes are applied in the head portion of the train, the braking action at the rear of the train tends to hold back the run- 75

ning in of train slack and thus aid in gently gathering the train slack.

In the rear portion of the train, the abutment 31 is operated upon a predetermined increase in 5 brake cylinder pressure the same as in the front portion of the train, but since the selector slide valve 25 and lever 32 are in the position shown in Fig. 1, the operation of said abutment merely moves the push rod 38 relative to the lever 32, due 10 to the slot 39 provided in the end of said rod for this purpose.

The service reduction in brake pipe pressure in the emergency piston chamber 15 permits the 15 pressure of fluid in valve chamber 16 to move the piston 14 and auxiliary slide valve 21 relative to the main slide valve 20. This movement ceases when a port 108 is moved sufficiently into registry with port 109 through the main slide valve 20 to permit quick action chamber pressure in valve 20 chamber 16 to reduce to the atmosphere by flow 25 through port 109 and atmospheric passage 110 at substantially the same rate as the brake pipe pressure is reduced. Then when the pressure in valve chamber 16 is reduced to a degree slightly 30 lower than the reduced brake pipe pressure acting in piston chamber 15, the piston 14 is operated to move the slide valve 21 in the reverse direction and lap port 109 so as to prevent further flow of fluid under pressure from the valve 35 chamber 16 to the atmosphere.

In order to effect a release of fluid under pressure from the brake cylinder 86, the brake pipe pressure is increased and the triple valve device 2 and emergency valve device 3 are thereby moved 40 to release position in which fluid under pressure is permitted to flow back from the emergency reservoir 78 through passage 77, port 74 in the triple valve slide valve 12 and port 73 to the auxiliary reservoir. Port 14 is also connected 45 through passage 75 to the inshot reservoir 76, so that the pressures in said reservoir are first permitted to substantially equalize after which they are charged to brake pipe pressure by the supply 50 of fluid under pressure from the brake pipe through the feed passage 71 to valve chamber 9, as hereinbefore described. In release position of the emergency valve device, the valve chamber 16 and quick action chamber 17 are also charged to 55 brake pipe pressure by flow of fluid under pressure from piston chamber 15 through passage 82, past check valve 83 and through port 84 to valve chamber 16.

In the release position of the triple valve device, fluid under pressure is vented from the brake 60 cylinder 86 through pipe and passage 87, cavity 89 in the selector slide valve 25, passage 90, cavity 91 in the triple valve 12, passage 92, choke 65 plug 93 and atmospheric passage 94.

In charging the brake pipe, the rapid rate of 70 increase in brake pipe pressure at the head end of the train operates the abutment 27 to shift the selector slide valve 25 from the final application position shown in Fig. 1 to the initial application position shown in Fig. 3, while at the rear end of the train where the rate of increase in brake pipe pressure is slow the selector slide valve 25 remains in the position shown in Fig. 1, as hereinbefore described. The movement of the selector slide valve to the position shown in Fig. 3 75 closes communication from passage 87 to passage 90, so that upon movement of said slide valve to said position, the release of fluid under pressure from the brake cylinder is retarded through the choke plug 88.

In effecting an emergency application of the

brakes by a sudden reduction in brake pipe pressure, the triple valve device 2, and the selector valve device and selector cut-out device 5 operate in the same manner as in effecting a service application of the brakes. 5

Upon a sudden reduction in brake pipe pressure in the emergency piston chamber 15, the pressure of fluid in valve chamber 16 shifts the emergency piston 14 and slide valves 20 and 21 to emergency position in which said piston engages a gasket 111. In this position, the main slide valve 20 uncovers passage 112 which permits fluid under pressure to flow from the valve chamber 16 and the connected quick action chamber 17 through said passage to the vent valve piston 15 chamber 62. The pressure of fluid thus supplied to chamber 62 operates piston 60 to unseat the vent valve 58, which permits fluid under pressure to rapidly flow from the brake pipe 8 to the atmosphere through passage 66, chamber 59, past 20 the valve 58 to chamber 64 and from thence through the atmospheric passage 65. A sudden local reduction in brake pipe pressure is thus effected for propagating quick action through a train in the usual well known manner. 25

In the emergency position of slide valve 20, a cavity 114 connects passage 77 from the emergency reservoir 78 to passage 90 to which fluid under pressure is supplied by the triple valve device 2 from the auxiliary reservoir 10. Fluid under pressure is thus permitted to flow to the brake cylinder 86 from the emergency reservoir 78 as well as from the auxiliary reservoir 10, and a high emergency brake cylinder pressure is obtained by equalization of the pressures in said 30 reservoirs and brake cylinder. 35

Fluid under pressure supplied to the vent valve piston chamber 62 from the emergency valve chamber 16 gradually flows to the atmosphere through a port 116 in piston 60, chamber 40 63, chamber 64 and atmospheric passage 65. The pressure in valve chamber 16 is thus gradually reduced, and when reduced to a predetermined pressure, the pressure of a spring 117 moves the piston 14 and slide valves 21 and 22 downwardly 45 to emergency lap position in which the emergency reservoir passage 77 is disconnected from passage 90, but this does not occur until after equalization of the emergency reservoir pressure and auxiliary reservoir pressure into the brake 50 cylinder. 55

When the pressure in the vent valve piston chamber 62 becomes reduced to a low degree, by the flow of fluid under pressure from said chamber to the atmosphere, the spring 61 seats the vent valve 58, so that when desired, a release of the brakes may be effected. 55

In order to effect a release of fluid under pressure from the brake cylinder 10 and to recharge the brake system after an emergency application of the brakes, the brake pipe pressure is increased, causing the triple valve device and emergency valve device to move to their release position in which the auxiliary reservoir 10, emergency reservoir 78, inshot reservoir 76 and quick 60 action chamber 17 are again charged with fluid under pressure in the same manner as described in initially charging the brake equipment. Also fluid under pressure is vented from the brake cylinder 86, and the selector valve device is operated in the same manner as in effecting a release of the brakes after a service application. 65

In order to operate this brake controlling valve device in a short train where it is not desired to retard the build-up of brake cylinder pressure 70 75

in the front end of the train, the brake pipe pressure is increased to a degree higher than employed in operating a long train. The brake pipe pressure may be increased, for instance, to 77 pounds, 5 or seven pounds higher than carried in long train operation. As a result, the brake equipment is charged to 77 pounds, and this pressure which is obtained in the emergency reservoir 78 and acts on the cut-out abutment 48, within the 10 seat rib 53, is adapted to overcome the pressure of spring 52 and move said abutment away from said seat rib. The full area of said abutment is then exposed to emergency reservoir pressure which promptly moves said abutment into engagement with a stop rib 118.

This movement of the abutment 48 is adapted to act through spring 56 and move the plunger 47 into the space between the casing and the lug 46 on the lever 32, as shown in Fig. 5. With 20 the lever 32 thus blocked, the movement of the slide valve 25 by a rapid rate of increase in brake pipe pressure in charging the brake pipe, compresses spring 36. Then when the auxiliary reservoir 16 becomes charged up to within a certain 25 degree of the pressure in the brake pipe 8, and the selector valve abutment 27 is moved from the position shown in Fig. 2 to that shown in Fig. 1, as hereinbefore described, the spring 36 moves the slide valve 25 back to the position shown in 30 Fig. 1, so that an unretarded build-up of brake cylinder pressure will be obtained at the front end of the train when an application of the brakes is effected.

In initially charging a short train, the lever 32 will be rotated by movement of the selector valve 25 at the head end of the train in the same manner as in charging a long train. This is due to the fact that the brake pipe pressure will build up more rapidly than the pressure in the 35 emergency reservoir 78, and as a result, lug 46 on said lever will be moved into the path of movement of plunger 47 and thus prevent said plunger from moving to its intended position. It is then necessary before moving the train to effect 40 a service application of the brakes and cause the abutment 37 to be operated to rotate the lug 46 out of the path of movement of the plunger 47 which will then be promptly moved to its upper 45 position, by means of spring 56, in which position it will function, as hereinbefore described, to cause the selector slide valve 25 to be in the unrestricted application position.

Spring 52 is of considerable value, and it would be undesirable to have a pressure equal to the 50 pressure of said spring acting through the plunger 47 in the lug 46 for the reason that it would tend to warp or break the mechanism and further would exert such a force on said lug as to make it difficult for the abutment 37 to move said 55 lug out of the path of movement of the plunger 47. However, by employing the telescopic construction shown, this undesirable condition is gotten away from and the plunger 47 is at no time subject to a pressure exceeding that of spring 56 which is of only light value.

From the above description, it will be noted 60 that we have provided a brake controlling valve device having improved means which are operated, by the rapid rate of increase in the brake pipe pressure at the head end of a train, in such a manner as to retard or delay the application of brakes at the head end of the train upon a reduction in brake pipe pressure. It is intended 65 that the delay means shall be employed in operating long trains, but in operating short trains

where the delayed brake application is not desired, the delay means are rendered ineffective by cut-out means which are operated by the higher pressure carried in short train service.

The subject matter relating to the controlled 5 build-up of brake cylinder pressure in effecting an application of the brakes is broadly claimed in the pending application of Clyde C. Farmer, Serial No. 612,465, filed May 20, 1932.

While one illustrative embodiment of our invention has been described in detail, it is not our intention to limit its scope to this embodiment or otherwise than by the terms of the appended 10 claims.

Having now described our invention, what we 15 claim as new and desire to secure by Letters Patent, is:

1. In a fluid pressure brake, the combination with a brake pipe and a brake cylinder, of a brake controlling valve device operative upon a reduction 20 in brake pipe pressure to supply fluid under pressure to said brake cylinder, and a valve device for controlling the communication through which fluid under pressure is supplied from said brake controlling valve device to said brake cylinder, 25 said valve device being subject to and directly controlled by the pressure of fluid in said brake pipe and movable upon a predetermined increase in brake pipe pressure to a position in which the supply of fluid under pressure from said brake 30 controlling valve device to said brake cylinder is delayed.

2. In a fluid pressure brake, the combination with a brake pipe and a brake cylinder, of a brake controlling valve device operative upon a reduction 35 in brake pipe pressure to supply fluid under pressure to said brake cylinder, a valve having a position for retarding the supply of fluid under pressure from said brake controlling valve device to said brake cylinder, and a movable abutment directly controlled by and operated by an increase in brake pipe pressure for moving said valve to said position.

3. In a fluid pressure brake, the combination with a brake pipe and a brake cylinder, of a brake 45 controlling valve device operative upon a reduction in brake pipe pressure to supply fluid under pressure to said brake cylinder, a valve having a position for retarding the supply of fluid under pressure from said brake controlling valve device 50 to said brake cylinder, and a movable abutment subject to and directly controlled by brake pipe pressure and operative upon a predetermined increase in brake pipe pressure to move said valve to said position.

4. In a fluid pressure brake, the combination with a brake pipe and a brake cylinder, of a brake controlling valve device operative upon a reduction 60 in brake pipe pressure to establish a communication through which fluid under pressure is supplied to said brake cylinder, a valve for controlling said communication and movable to a position for restricting said communication, and a movable abutment directly controlled by and operative by a predetermined increase in brake 65 pipe pressure for moving said valve to said position.

5. In a fluid pressure brake, the combination with a brake pipe and a brake cylinder, of a brake controlling valve device operative upon a reduction 70 in brake pipe pressure to establish a communication through which fluid under pressure is supplied to said brake cylinder, a choke plug in said communication, a valve for controlling a by-pass around said choke plug, and a movable 75

abutment directly controlled by and operated by an increase in brake pipe pressure for operating said valve to close said by-pass.

6. In a fluid pressure brake, the combination with a brake pipe, a brake cylinder, and an auxiliary reservoir, of a brake controlling valve device operative upon a reduction in brake pipe pressure to establish a communication through which fluid under pressure is supplied from said auxiliary reservoir to said brake cylinder, a valve having one position for retarding the flow of fluid under pressure through said communication and another position for permitting an unrestricted flow of fluid under pressure through said communication, and a movable abutment subject to and directly controlled by the opposing pressures of the brake pipe and auxiliary reservoir and operative upon a predetermined increase in brake pipe pressure to move said valve to the first mentioned position.

7. In a fluid pressure brake, the combination with a brake pipe and a brake cylinder, of a brake controlling valve device operative upon a reduction in brake pipe pressure to establish a communication through which fluid under pressure is supplied to said brake cylinder, valve means operated by a predetermined increase in brake pipe pressure for retarding the flow of fluid under pressure through said communication upon a reduction in brake pipe pressure, and a movable abutment subject to the pressure of fluid supplied to said brake cylinder and operative upon a predetermined increase in brake cylinder pressure for operating said valve means to permit an unrestricted flow of fluid under pressure from said brake controlling valve device to said brake cylinder.

8. In a fluid pressure brake, the combination with a brake pipe and a brake cylinder, of a brake controlling valve device operative upon a reduction in brake pipe pressure to establish a communication through which fluid under pressure is supplied to said brake cylinder, a movable valve for controlling said communication and having a position in which fluid under pressure is supplied through said communication to said brake cylinder at one rate and another position in which fluid under pressure is supplied through said communication to said brake cylinder at another rate, a movable abutment operated by a predetermined increase in brake pipe pressure for moving said valve to the first mentioned position, and another movable abutment operative by a predetermined increase in brake cylinder pressure for moving said valve to the second mentioned position.

55 9. In a fluid pressure brake, the combination with a brake pipe and a brake cylinder, of a brake controlling valve device operative upon a reduction in brake pipe pressure to supply fluid under pressure to said brake cylinder to effect an application of the brakes, and means for varying the rate at which fluid under pressure is supplied from said valve device to said brake cylinder, said means comprising a valve directly controlled by brake pipe pressure and operative upon a predetermined increase in brake pipe pressure for providing one rate and operative upon a predetermined increase in brake cylinder pressure, in effecting an application of the brakes, for providing another rate.

70 10. In a fluid pressure brake, the combination with a brake pipe and a brake cylinder, of a brake controlling valve device operative upon a reduction in brake pipe pressure to supply fluid under pressure to said brake cylinder at a certain rate, a valve for controlling said rate and operative to

change said rate, a lever for operating said valve, and an abutment subject to brake cylinder pressure for operating said lever.

11. In a fluid pressure brake, the combination with a brake pipe and a brake cylinder, of a brake controlling valve device operative upon a reduction in brake pipe pressure to supply fluid under pressure to said brake cylinder at a certain rate, a valve for controlling said rate and operative to change said rate, a lever for operating said valve, a spring, and a movable abutment subject to the opposing pressures of said spring and brake cylinder pressure for operating said lever.

12. In a fluid pressure brake, the combination with a brake pipe and a brake cylinder, of a brake controlling valve device operative upon a reduction in brake pipe pressure to supply fluid under pressure to said brake cylinder at a certain rate, a valve for controlling said rate and operative to change said rate, a lever for operating said valve, and a fluid pressure operated abutment for operating said lever and having a chamber at one side, said brake controlling valve device being operative upon a reduction in brake pipe pressure to connect said chamber to said brake cylinder and upon an increase in brake pipe pressure to vent said chamber.

13. In a fluid pressure brake, the combination with a brake pipe and a brake cylinder, of a brake controlling valve device operative upon a reduction in brake pipe pressure to supply fluid under pressure to said brake cylinder, and means for varying the rate at which fluid under pressure is supplied from said valve device to said brake cylinder, said means comprising a valve having a position for providing a certain rate, a lever for moving said valve to another position for providing a different rate, a movable abutment operative by a predetermined increase in brake cylinder pressure for moving said lever and having a lost motion connection with said lever, and another movable abutment operative by a predetermined increase in brake pipe pressure for moving said valve from the second mentioned position to the first mentioned position independently of said lever.

14. In a fluid pressure brake, the combination with a brake pipe and a brake cylinder, of a brake controlling valve device operative upon a reduction in brake pipe pressure to supply fluid under pressure to said brake cylinder, means for controlling the flow of fluid under pressure from said brake controlling valve device to said brake cylinder, said means comprising a valve movable to one position for providing a certain rate of flow of fluid under pressure from said brake controlling valve device to said brake cylinder, and movable to another position for providing a different rate of flow of fluid under pressure from said brake controlling valve device to said brake cylinder, a movable abutment operated by a predetermined increase in brake pipe pressure for moving said valve to the first mentioned position, and fluid pressure controlled means for moving said valve from the first mentioned position to the second mentioned position when the brake pipe is charged with fluid at a pressure exceeding a predetermined degree.

15. In a fluid pressure brake, the combination with a brake pipe and a brake cylinder, of a brake controlling valve device operative upon a reduction in brake pipe pressure to supply fluid under pressure to said brake cylinder, means for controlling the flow of fluid under pressure from said brake controlling valve device to said brake cylinder,

- der, said means comprising a valve movable to one position for providing a certain rate of flow of fluid under pressure from said brake controlling valve device to said brake cylinder, and movable 5 to another position for providing a different rate of flow of fluid under pressure from said brake controlling valve device to said brake cylinder, a movable abutment operated by a predetermined increase in brake pipe pressure for moving said 10 valve to the first mentioned position, a member at one time movable with said valve, a spring interposed between said member and valve, and means operated by fluid under pressure, when the brake pipe is charged with fluid at a pressure exceeding a predetermined degree for preventing 15 said member from moving with said valve.
16. In a fluid pressure brake, the combination with a brake pipe and a brake cylinder, of a brake controlling valve device operative upon a reduction 20 in brake pipe pressure to supply fluid under pressure to said brake cylinder, means for varying the rate at which fluid under pressure is supplied from said brake controlling valve device to said brake cylinder, said means comprising a valve 25 having one position for providing a certain rate and another position for providing another rate; a movable abutment operated by a predetermined 30 brake pipe pressure for moving said valve to the first mentioned position, a spring engaging said valve, a member engaging said spring and at one time movable with said spring and valve by said abutment, and means operated by fluid under pressure when the brake pipe is charged to a pressure exceeding a predetermined degree for 35 locking said lever against such movement for causing said spring to move said valve from the first mentioned position to the second mentioned position.
17. In a fluid pressure brake, the combination 40 with a brake pipe and a brake cylinder of a brake controlling valve device operative upon a reduction in brake pipe pressure to supply fluid under pressure to said brake cylinder, means for varying the rate at which fluid under pressure is supplied 45 from said brake controlling valve device to said brake cylinder, said means comprising a valve having one position for providing a certain rate and another position for providing another rate; a movable abutment operated by a predetermined 50 brake pipe pressure for moving said valve to the first mentioned position, a spring for moving said valve from the first mentioned position to the second mentioned position and at one time movable with said valve, a member engaging said 55 spring and at one time movable with said valve and having a position for causing said spring to be compressed by the movement of said valve, and means operated by fluid under pressure when the brake pipe is charged to a pressure exceeding 60 a predetermined degree for locking said member in the last mentioned position.
18. In a fluid pressure brake, the combination 65 with a brake pipe, a brake cylinder, an auxiliary reservoir, and another reservoir, of a brake controlling valve device operative upon a reduction in brake pipe pressure to supply fluid under pressure from said auxiliary reservoir to said brake cylinder, and operative upon an increase in brake 70 pipe pressure to supply fluid under pressure from the brake pipe to said reservoirs and to vent fluid under pressure from said brake cylinder, a valve for controlling the supply of fluid under pressure from said brake controlling valve device to said 75 brake cylinder and having one position for providing a certain rate of supply and another posi-
- tion for providing a different rate of supply, a movable abutment subject to the opposing pressures of the auxiliary reservoir and brake pipe and operative to move said valve to the first mentioned position upon a predetermined increase 5 in brake pipe pressure over auxiliary reservoir pressure, a spring engaging said valve and operative when compressed to move said valve from the first mentioned position to the second mentioned position when the pressure differential on 10 said abutment is reduced to a predetermined degree, a member engaging said spring and movable with said valve to the first mentioned position, a movable abutment operatively connected to said member and a subject to the pressure of fluid in 15 said brake cylinder and operative upon a predetermined increase in brake cylinder pressure to move said member for compressing said spring, means operative to prevent movement of said member to the first mentioned position, and a 20 movable abutment operative by the pressure of fluid in said other reservoir for operating said means when said other reservoir is charged with fluid at a pressure exceeding a predetermined 25 degree.
19. In a fluid pressure brake, the combination with a brake pipe, a brake cylinder, an auxiliary reservoir, and another reservoir, of a brake controlling valve device operative upon a reduction 30 in brake pipe pressure to supply fluid under pressure from said auxiliary reservoir to said brake cylinder, and operative upon an increase in brake pipe pressure to supply fluid under pressure from the brake pipe to said reservoirs and to vent fluid under pressure from said brake cylinder, a valve 35 for controlling the supply of fluid under pressure from said brake controlling valve device to said brake cylinder and having one position for providing a certain rate of supply and another position for providing a different rate of supply, a 40 movable abutment subject to the opposing pressures of the auxiliary reservoir and brake pipe and operative to move said valve to the first mentioned position upon a predetermined increase in brake pipe pressure over auxiliary reservoir pressure, a spring engaging said valve and operative 45 when compressed to move said valve from the first mentioned position to the second mentioned position when the pressure differential on said abutment is reduced to a predetermined degree, a 50 member engaging said spring and movable with said valve to the first mentioned position, a movable abutment operatively connected to said member and subject to the pressure of fluid in said 55 brake cylinder and operative upon a predetermined increase in brake cylinder pressure to move said member for compressing said spring, means operative to prevent movement of said member to the first mentioned position, a spring, a movable abutment for operating said means and having a telescopic connection therewith, said abutment being subject on one side to the pressure of said spring and on the other side to the pressure of fluid in said other reservoir, and operative 60 when said other reservoir is charged with fluid at a pressure exceeding the pressure of said spring for operating said means to prevent movement of said member.
20. In a fluid pressure brake, the combination with a brake pipe, a brake cylinder, an auxiliary 70 reservoir and another reservoir, of a brake controlling valve device operative upon a reduction in brake pipe pressure to establish one communication through which fluid under pressure is supplied from said auxiliary reservoir to said brake 75

cylinder and another communication through which fluid under pressure is vented from said other reservoir to said brake cylinder, and operative upon an increase in brake pipe pressure to close said communications and to supply fluid under pressure from said brake pipe to said reservoirs and to vent fluid under pressure from said brake cylinder, of a valve for controlling said communications and operative in one position to retard the flow of fluid under pressure through the first mentioned communication and to permit unrestricted flow through the second mentioned communication, and operative in another position to permit unrestricted flow of fluid under pressure through the first mentioned communication and to close the second mentioned communication, a movable abutment subject to the opposing pressures of the auxiliary reservoir and brake pipe and operative upon a predetermined increase in brake pipe pressure to move said valve to the first mentioned position, and another movable abutment subject to brake cylinder pressure and operative to move said valve to the second mentioned position upon a predetermined increase in brake cylinder pressure.

21. In a fluid pressure brake, the combination with a brake pipe adapted at one time to carry fluid at a predetermined pressure and at another time to carry fluid at a predetermined higher pressure, and a brake cylinder, of a brake controlling valve device operative upon a reduction in brake pipe pressure to supply fluid under pressure to said brake cylinder, means for controlling the flow of fluid under pressure from said brake controlling valve device to said brake cylinder, said means comprising a valve movable to one position for providing a certain rate of flow and movable to another position for providing a different rate of flow, a movable abutment operative by a predetermined rate of increase in brake pipe pressure for moving said valve to the first mentioned position, and fluid pressure controlled means operative when the brake pipe is charged to said predetermined higher pressure for moving said valve from the first mentioned position to the second mentioned position.

22. In a fluid pressure brake, the combination with a brake pipe, a brake cylinder, and a reservoir normally charged with fluid under pressure, of a brake controlling valve device operative upon a reduction in brake pipe pressure to supply fluid under pressure from said reservoir to said brake cylinder, and valve means for controlling the communication through which fluid under pressure is supplied from said reservoir to said brake cylinder and operative upon a predetermined increase in brake cylinder pressure to close said communication, said brake controlling valve device being operative upon a reduction in brake pipe pressure to supply fluid under pressure from said brake cylinder for operating said valve means.

23. In a fluid pressure brake, the combination with a brake pipe, a brake cylinder, and a reservoir normally charged with fluid under pressure, of a brake controlling valve device operative upon a reduction in brake pipe pressure to supply fluid under pressure from said reservoir to said brake cylinder, and valve means operated by fluid under pressure supplied through said brake controlling valve device, when said brake controlling valve device is operated upon either a service or an emergency reduction in brake pipe pressure, for closing the communication through which fluid

under pressure is supplied from said reservoir to said brake cylinder.

24. In a fluid pressure brake, the combination with a brake pipe, a brake cylinder, an auxiliary reservoir, and another reservoir, of a brake controlling valve device operative upon a reduction in brake pipe pressure to supply fluid under pressure from said auxiliary reservoir to said brake cylinder and from said other reservoir to said brake cylinder, a valve mechanism conditioned according to its position in a train to either open or close communication through which fluid is supplied from said other reservoir to the brake cylinder, and means operated upon a predetermined increase in brake cylinder pressure for effecting the movement of said valve mechanism to close said communication.

25. In a fluid pressure brake, the combination with a brake pipe, a brake cylinder, an auxiliary reservoir, and another reservoir, of a brake controlling valve device operative upon a reduction in brake pipe pressure to supply fluid under pressure from said auxiliary reservoir to said brake cylinder and from said other reservoir to said brake cylinder, a valve mechanism conditioned according to its position in a train for controlling the communication from said other reservoir to said brake cylinder, and an abutment operated upon a predetermined increase in brake cylinder pressure for operating said valve mechanism to close said communication.

26. In a fluid pressure brake, the combination with a brake pipe, a brake cylinder, an auxiliary reservoir, and another reservoir, of a brake controlling valve device operative upon a reduction in brake pipe pressure to supply fluid under pressure from said auxiliary reservoir to said brake cylinder and from said other reservoir to said brake cylinder, a valve for controlling the communication from said other reservoir to said brake cylinder, and an abutment, having a chamber at one side, for operating said valve to close said communication, said brake controlling valve device being operative upon a reduction in brake pipe pressure to supply fluid under pressure from said brake cylinder to said chamber for operating said abutment, said brake controlling valve device being operative upon an increase in brake pipe pressure to vent fluid under pressure from said chamber.

27. In a fluid pressure brake, the combination with a brake pipe and a brake cylinder, of a valve device operated upon a reduction in brake pipe pressure to supply fluid under pressure to said brake cylinder to effect an application of the brakes and operated upon an increase in brake pipe pressure to vent fluid under pressure from said brake cylinder to effect a release of the brakes, and a valve element for controlling the rate at which fluid under pressure is supplied to said brake cylinder by the operation of said valve device, said valve element being movable by brake pipe pressure to one position for permitting flow from said valve device to said brake cylinder at one rate and movable by brake cylinder pressure to another position for permitting flow at another rate.

28. In a fluid pressure brake, the combination with a brake pipe and a brake cylinder, of a valve device operated upon a reduction in brake pipe pressure to supply fluid under pressure to said brake cylinder to effect an application of the brakes and operated upon an increase in brake pipe pressure to vent fluid under pressure from said brake cylinder to effect a release of the

- brakes, and a valve element for varying the rate at which fluid under pressure is supplied to said brake cylinder, said valve element being positioned upon an increase in brake pipe pressure 5 to retard the supply of fluid to the brake cylinder upon a reduction in brake pipe pressure, and operative upon a predetermined increase in brake cylinder pressure to accelerate the rate of supply of fluid under pressure to the brake cylinder.
- 10 29. In a fluid pressure brake, the combination with a brake pipe and a brake cylinder, of a valve device operated upon a reduction in brake pipe pressure to supply fluid under pressure to said brake cylinder to effect an application of the 15 brakes and operated upon an increase in brake pipe pressure to vent fluid under pressure from said brake cylinder to effect a release of the brakes, a valve for controlling communication through which fluid supplied by said valve device 20 is adapted to flow to said brake cylinder, a movable abutment operative by an increase brake pipe pressure for moving said valve to close said communication, and another movable abutment operative by brake cylinder pressure, only when 25 the brake cylinder pressure exceeds a predeter-
- mined degree, for moving said valve to open said communication.
30. In a fluid pressure brake, the combination with a brake pipe and a brake cylinder, of a valve device operated upon a reduction in brake pipe 5 pressure to supply fluid under pressure to said brake cylinder to effect an application of the brakes and operated upon an increase in brake pipe pressure to vent fluid under pressure from said brake cylinder to effect a release of the 10 brakes, a valve for controlling the flow of fluid from said valve device to said brake cylinder, and having one position for retarding such flow and another position for permitting such flow at a fast rate, a movable abutment operated by a rapid 15 increase in brake pipe pressure for shifting said valve to the position for retarding the flow of fluid to said brake cylinder, and another movable abutment operated upon a predetermined increase in brake cylinder pressure for shifting said valve 20 to the position for permitting the flow at the fast rate.
